UNITED STATES PATENT OFFICE.

PETER J. TERNES AND ROBERT HOHNBACH, JR., OF MILWAUKEE,
WISCONSIN.

ROCKING MEAT-CUTTER.

SPECIFICATION forming part of Letters Patent No. 433,056, dated July 29, 1890.

Application filed February 21, 1890. Serial No. 341,283. (No model.)

To all whom it may concern:

Be it known that we, PETER J. TERNES and ROBERT HOHNBACH, Jr., of Milwaukee, in the county of Milwaukee, and in the State of Wisconsin, have invented certain new and useful Improvements in Rocking Meat-Cutters; and we do hereby declare that the following is a full, clear, and exact description thereof.

Our invention relates to rocking meat-cutters; and it consists in certain peculiarities of construction, as will be fully set forth hereinafter, and subsequently claimed.

In the drawings, Figure 1 is a vertical longitudinal section of our improved meat-cutter with parts broken away and other parts in dotted lines. Fig. 2 is a plan view of the same, partially broken away and partially in section. Fig. 3 is a plan view of the mechanism for raising and lowering the meat-block, on an enlarged scale, parts being shown in section or broken away to better illustrate details of construction; and Fig. 4 is a detail sectional view on the line 4 4 of Fig. 1.

A is the base, from which rise two standards 25 or upright frames B B, which support the power-shaft C, the latter being provided with pulleys *a a* and a worm *b*, as shown. The worm *b* meshes with a horizontal worm-wheel *c* on the upper end of a vertical shaft D, which 30 is steadied in upper bearings *d* on the end of a bracket-arm *e*, projecting from one of the frames B. This shaft at its lower end is stepped in lower bearings *f*, just above which said shaft carries a belt-pulley *g* for rotating the meat-block E, as hereinafter explained.

F F' are a series of standards, preferably four in number, rising from the base A, to which they may be secured, as shown, by nuts *h*, passing through the base-flanges *i* of said 40 standards. The tops of the standards F F' are perforated for the reception of the hubs *j* of screw-bolts G G G', which carry horizontal sprocket-wheels *k*, mounted rigidly thereon above said standards. Fastening-collars *k'* surround these bolts near their lower ends, just below the tops of the standards F F' 45, and the standard F' is shorter than the others and supports the hub of a horizontal hand-wheel H. This wheel is mounted on the screw-bolt G' just below the sprocket-wheel *k*, so

that all of said sprocket-wheels may be on the same horizontal plane, and the said wheels are all connected by an endless sprocket-chain I, as shown.

J is a bridge or arch standard, also rising 55 from the base A, and preferably secured thereto by nuts *h'*, passing through the lower flanges *i'* of said standard. This standard is provided with a central socket *j'* for a vertical spindle K, which is preferably hollow, being thus 60 equally strong and inexpensive, and after passing downward through the socket *j'* the spindle receives and passes through a horizontal pulley I', suitably secured to the spindle beneath the arch-standard J. The end of 65 the spindle is stepped into a socket *j''* in a short standard J', which rises from the base A beneath the center of the arch-standard J. The lower extremity of this spindle preferably rests upon a steel button *g'* in the bottom of the socket *j''*, which serves to decrease 70 friction and wear, and the spindle has an eccentrically-secured top K', also preferably hollow for the sake of strength and cheapness. This top K' is suitably secured by a key *f'*, 75 for example, to a circular casing II', having an upper horizontal flange or flanges *e'*, by means of which and nuts and bolts *d' c'* the said casing is secured to the under side of a circular plate E'. This circular plate supports 80 the meat-block E and has a circumferential vertical flange *b'*, provided at equidistant points (preferably four in number) with transverse screw-threaded perforations to receive screw-bolts *a'*, as shown. These 85 bolts have brake-shoes *a''* at their inner ends, said shoes being concaved to conform to the adjacent surface of the meat-block, and at their outer ends said screws have handles or thumb-pieces *b''* at the other end, whereby the 90 said meat-block may be centered or adjusted on its supporting-plate and securely held in the desired position.

The supporting-plate E' of the meat-block is itself supported as follows: L is the hub of 95 a spider having a series (as four) of flanged arms L' L'. This hub (in the position of parts shown in Fig. 1) rests on top of the standard J, and said arms, after extending horizontally for the greater portion of their length, curve 100

upward at their ends, as best shown in Fig. 1, and are provided at their extremities with depressions and seats $l^1 l^2$ for anti-friction rollers m^1 and their journals m^2 , said arms being transversely and vertically perforated, as shown at $m m$, for the passage therethrough of the vertical screw-bolts $G G'$. The lower part of said perforations $m m$ are enlarged and provided with polygonal faces for the reception of nuts $n n$, so that the upper portion of said perforations m may be smooth, thereby reducing the cost as compared with screw-threading the perforations through the arms $L' L'$. These arms with their hub L may be simply cast in one piece complete, the nuts n receiving the screw-bolts, while the supporting-plate E' of the meat-block, which may have an annular bottom re-enforce n' , if desired, rests squarely and evenly on the anti-friction rollers $m^1 m^2$. A belt M connects the pulleys I' and g and transmits power from the vertical shaft D to the said spindle K , all as best shown in Fig. 1.

$N N$ represent fly-wheels mounted on the ends of the power-shaft C outside of the upright frames $B B$, and these wheels are pivotally connected by means of wrist-pins o on their peripheries and rods $O O$ to the knife-frame P of our device, as follows: The said frame, which is preferably an open and practically rectangular one, has standards p rising from its ends, the upper end of each of said standards being perforated transversely for the reception of one half o' of a pivot-bolt. The other half of the bolt o^2 is larger than the part o' and fits a corresponding perforation through the rod O , said pivot-bolt having a solid collar p^3 between its parts $o' o^2$, and screw-threaded ends which receive nuts $p^1 p^2$. The end which receives the nut p^2 is preferably reduced in diameter, and has a washer o^3 interposed between said nut p^2 and the part o^2 of the said pivot-bolt. Beyond this point of connection with the said pivot-bolt the rod O is continued at O' , and is provided near its extreme free end with a pin q , designed to travel in the curved slot q' in the curved guide-arm Q . This guide-arm has a lower base-flange q^2 , which rests on the end of the frame P , and is secured thereto by nuts and bolts, as shown at $q^3 q^4$. The rod-extension O' and the guide Q are each provided with perforations $r r'$, which register when the parts are in the position shown in Figs. 1 and 2, and by slipping a pin (which may be kept in another perforation r^2) through the perforations $r r'$ the parts can be locked in said position at any time, if desired, as when cleaning or repairing the machine.

$R R R$ represent a series of knives having convex cutting-edges adjustably suspended from the knife-frame P by means of hangers $S S$, one at each end of each knife. These hangers have shanks passing through screw-threaded perforations in the sides of the frame P and bifurcated lower ends $s s$, which straddle the backs of the knife-blades, said ends being bolted or riveted thereto. Nuts s'

s^2 embrace the shanks of the hangers S above and below the frame P , so as to secure the said hangers in their adjusted positions.

T is a lever formed in one piece or rigid with its handle T' , the two portions inclining in opposite directions away from each other, and being pivoted, as shown at t , to one of the upright frames B . The free end of the lever terminates in a flat head t' , on which (in the position of parts shown in the drawings) there rests a projection P' , which is secured on the knife-frame P . M' is a gravity-catch, also pivoted to the said frame B and serving to hold and lock the arm T' of the lever in the position shown. We have also shown a perforation u in said lever-arm and another u' in the frame B , and when these perforations are brought into register with each other the adjacent side of the knife-frame will be raised, and by slipping a pin through both of said perforations the parts can be locked in that position.

When deemed necessary, one or more additional curved guides, such as is shown in dotted lines at U in Fig. 1, may be attached to any convenient part of the frame-work of the machine—such as the upright frames B —the said guide or guides U projecting in a direction opposite that of the guides Q , already described. The guide U is much longer than the guide Q , and is provided with a curved slot V , similar to the slot q . To render said guide or guides U effective, there must be for each guide an extension W on the knife-frame P and a pin X on said extension working in the said slot V , all as shown in Fig. 1 in dotted lines.

The operation of our machine will be readily understood from the foregoing description of its construction. When power is applied to the shaft C , the fly-wheels N revolve, and by means of the rods O , wristed thereto and pivotally connected to the knife-frame P , the latter, with its knives, is given a rocking motion, this motion being controlled by means of the engagement of the rod-extensions O' and curved slotted guides Q , (as well as the engagement of the parts $U V W X$, if the same be used,) as the said knives rock on the meat-block E . The latter is rotated eccentrically by means of the described construction and connection of parts, thereby constantly changing the position of the meat upon said block.

A very important feature of the invention is the construction described, whereby by simply turning a hand-wheel the meat-block will be automatically and evenly raised or lowered, the described slotted guides and attachments absolutely preventing the knives from accidentally slipping out of proper position.

Having thus described our invention, what we claim as new, and desire to secure by Letters Patent, is—

1. In a meat-cutting machine, a meat-block carrying a cylindrical socket secured cen-

trally to its under side, in combination with a vertical driving-spindle carrying at its upper end an eccentric top piece connected at one side to one of the sides of the said socket, substantially as described.

5. 2. In a meat-cutting machine, a rocking knife-carrying frame having an upwardly-extending standard and an upwardly and inwardly extending longitudinally-slotted 10 guide-arm secured at its base to said knife-carrying frame, and an actuating rod or link working at its end in the slot of the guide-arm and pivoted back of said end upon the standard, substantially as described.

15 3. In a meat-cutting machine, a prolonged cylindrical socket attached centrally to the under side of the meat-block and a vertical actuating-shaft having an eccentric top piece working within said casing, a number of vertical lifting-screws engaging the block and carrying sprocket-wheels, an endless chain connecting said wheels, and a hand-wheel mounted upon one of said screws, substantially as described.

25 4. The combination, with a rocking knife-carrying frame and a bent lever connected at one end to the frame and pivoted upon the power-shaft standard, of means, substantially as described, for retaining the outer end of 30 said lever in raised and depressed position relative to the shaft-standard, as set forth.

5. In a rocking meat-cutter, the combination, with a series of standards and vertical screw-bolts passing therethrough and carrying sprocket-wheels in horizontal line with each other, of an arched standard having a central socket, a spindle passing therethrough and carrying a horizontal pulley and terminating in an eccentrically-secured top, a cylindrical socket surrounding said top, a circular plate secured to said casing, a meat-block resting on said plate, a spider having arms provided with anti-friction rollers supporting said plate and perforated and carrying nuts for the reception of the said screw-bolts, a sprocket-chain engaging with and connecting all of said sprocket-wheels, a power-belt on said pulley, and a hand-wheel on one of said screw-bolts, substantially as set forth.

40 45 50 In testimony that we claim the foregoing we have hereunto set our hands, at Milwaukee, in the county of Milwaukee and State of Wisconsin, in the presence of two witnesses.
